UNITED STATES PATENT OFFICE.

JEROME C. HUNSAKER, OF WASHINGTON, DISTRICT OF COLUMBIA, ASSIGNOR TO THE GOVERNMENT OF THE UNITED STATES.

AEROPLANE FLOTATION DEVICE.

Application filed August 11, 1921. Serial No. 491,449.

To all whom it may concern:

Be it known that I, JEROME C. HUNSAKER, a citizen of the United States, residing at Washington, District of Columbia, have invented new and useful Improvements in Aeroplane Flotation Devices, of which the following is a specification.

This invention relates to improvements in aeroplanes and more particularly to a device 10 for floating aeroplanes which normally have no provision for landing in the water.

One of the objects of the present invention is to provide an attachment for aeroplanes of simple and practical construction 15 which may be easily and quickly applied to aeroplanes which allow them to float on the water in the event that a landing has to be made for any reason whatsoever.

It is desirable to use land planes provided 20 with landing wheels for flying off ships but if these planes are used ordinarily and forced to land, for any reason, in the water, they will float only so long as there is sufficient buoyancy given the plane by reason of 25 the air which is contained and trapped within the interior of the wings.

In the case of metal aeroplanes, it is very probable that the wing covering would not be water tight and, in that event, the plane 30 would sink almost immediately with consequent danger to the personnel operating the plane.

It may have been attempted to employ 35 devices of the above general character for accomplishing flotation in the water but such mechanisms have been unsatisfactory partly for the reason that they require complicated gear or apparatus within the fuselage and fixed or permanently installed air chambers 40 inside the fuselage. Such apparatus is impractical for many reasons and the present invention is designed to overcome the objections heretofore experienced by providing an attachment which may be easily and 45 quickly applied just prior to flight if desired to any land plane as well as a device which may be equally easily removed after it has served its purpose.

Other objects will be in part obvious and 50 in part pointed out in connection with the annexed sheets of drawings illustrating one of various possible embodiments of the invention and wherein like characters denote corresponding parts in the several views.

55 In these drawings, Figure 1 is a perspec-

tive view showing an aeroplane in flight equipped with the present invention.

Figure 2 is a detail perspective view, partly in section, showing one of the wings with the flotation bag secured thereto. 60

Figure 3 is a longitudinal sectional view of the apparatus applied to the wing, the wing being shown in transverse section.

Referring now to the drawing in detail the aeroplane of the usual land type is provided 65 with a lower wing 5, landing or take-off wheels 6 mounted upon the usual struts and supports 7.

The present invention resides largely in the inflatable air bag 8 which is attached to 70 and fitted around the wing 5 of the aeroplane. Preferably two of the air bags were employed one at each side of the fuselage 10. The only provisions required on the wing to take this air bag are suitable strips such 75 as canvas or the like which are firmly secured to and through the wings. Two or more of such strips are provided for each air bag. The air bag itself may be composed of one bag or a bag with a diaphragm 80 11 as shown in Figure 3 or a number of internal bladders or diaphragms to subdivide the bag into small compartments. The bag is preferably streamlined in shape so as to cut down its air resistance as much as possible. Provision is made for securing the air bag to such material permanently attached to the wings as above stated by means of lacings 12 or other desired fastening 85 means. The bag itself may be secured at 90 the outside points where it lies adjacent to the wing or in the event of a very large and wide bag it would be attached to the wing in a deflated condition which would permit any number of lacing strips to be 95 applied at intervals along the wing beneath the air bag. In the latter case the air bag could be inflated after it had been securely laced to the wing as by means of the valves 13. In the event of a plurality of compartments within the airbag it would, of course, be necessary to provide a valve for each compartment as shown in Figure 3. 100

It will thus be seen that the present invention provides a simple and practical attachment adapted to be easily and quickly attached to the wings of an aeroplane for use at sea when desired. 105

What I claim is:—

1. In combination with an aeroplane, 110

- means for providing flotation thereof, comprising an air bag mounted upon and encircling said wing.
2. In combination with an aeroplane, means for providing flotation thereof by a plurality of air bags secured to the lower wing, the air bag partially enclosing the wing on both top and bottom sides thereof and gaining support therefrom.
- 10 3. In combination with an aeroplane, means for providing flotation thereof by a plurality of air bags secured to the lower wing, the air bag partially enclosing the wing on both top and bottom sides thereof and gaining support therefrom, said air bag being provided with a plurality of air tight compartments.
- 20 4. In combination with an aeroplane, means for providing flotation thereof by a plurality of air bags secured to the lower wing, the air bag partially enclosing wing on both top and bottom sides thereof and gaining support therefrom, said bag being provided with a plurality of air tight compartments and means whereby each of said compartments may be filled as desired.
- 25 5. In combination with an aeroplane, an attachment therefor for providing flotation comprising a detachable air bag adapted to partially surround the wing and positioned both on the upper and under surfaces thereof and means permitting said attachment to be easily and quickly applied or taken off.
- 30 6. In combination with an aeroplane having a lower wing, a flotation bag encircling both the top and bottom of the wing and adapted to be secured thereto, cooperating means on said bag and wing whereby the bag may be easily and quickly attached and detached.
- 35 7. In combination with an aeroplane having a lower wing, a flotation bag encircling both the top and bottom of the wing and adapted to be secured thereto, cooperating means on said bag and wing whereby the bag may be easily and quickly attached and detached, said bag containing a plurality of air tight compartments with means whereby they may be filled or deflated as desired.
- 40 50 Signed at Washington, District of Columbia.

JEROME C. HUNSAKER.
